UNITED STATES PATENT OFFICE.

SIGMUND ULLMAN, OF NEW YORK, N. Y.

MACHINE FOR PERFORATING CHECKS AND DRAFTS.

SPECIFICATION forming part of Letters Patent No. 252,550, dated January 17, 1882.

Application filed June 17, 1881. (No model.)

To all whom it may concern:

Be it known that I, SIGMUND ULLMAN, of the city, county, and State of New York, have invented a new and Improved Machine for 5 Perforating Checks and Drafts, of which the following is a specification.

The object of my invention is to provide a new and improved machine for perforating checks or drafts in such a manner that the 10 amount for which the check is drawn cannot be forged or raised.

The invention consists of a plate containing a series of loose punch-pins arranged in longitudinal rows marked "units," "tens," "hundreds," &c., and in transverse rows marked "0," "1," "2," "3," &c., which punch-pins fit into perforations in a die-plate below the punch-plate, and provided with a guide or gage for the end of the check or draft. Above each longitudinal row 15 there is a sliding bar with a beveled notch in its under surface, and with the numerals from 0 to 9 on its upper surface, one of which numerals is visible through an aperture in the top plate, this notch being so located that it will be 20 above the punch-pin corresponding to the number showing through the aperture, and when the punch-plate is depressed the punch-pins under the notches will not be depressed, and consequently the corresponding numbers on a 25 prepared check will not be punched, and will show the value of the check, whereas all the other numerals will be punched.

In the accompanying drawings, Figure 1 is a longitudinal elevation of my improved machine for perforating checks and drafts, the 30 perforating apparatus being shown in cross-section. Fig. 2 is a plan view of the perforating apparatus. Fig. 3 is a longitudinal sectional elevation of the same on the line xx , 35 Fig. 2. Fig. 4 is a plan view of a perforated check.

Similar letters of reference indicate corresponding parts.

The plate A is provided with a series of 40 punch-pins, B, loosely fitting in perforations in this plate, and arranged in longitudinal rows marked "units," "tens," "hundreds," &c., and in transverse rows marked "0," "1," "2," "3," &c., in the same manner as the ends of the checks 45 or drafts are provided with the numbers from 0 to 9, arranged in longitudinal rows marked

"units," "tens," "hundreds," &c. The punch-pins B are provided with beveled or conical heads C, and pass through corresponding perforations in a guide-plate, E, below the plate A, and attached to the top of the die-plate F, provided with perforations G, corresponding in position with the punch-pins of the plate A. The plate E is recessed on the under side, so that the check can be passed in between the plates E and F. A guide or gage, N, is held between these two plates at one end and serves to guide the check or draft in such a manner that the subdivisions or numbered squares of the check or draft agree with the punch-pins B. The 55 plate A is pressed upward from the plate E by spiral springs H.

A bar, T, with a beveled notch, O, in its lower surface and the numerals 0 to 9 in its upper surface, is contained and slides in a groove in the plate A above each longitudinal row of punch-pins, the sliding bars being held in these grooves by transverse plates P and P', the former of which is provided with an aperture, Q, above each bar T, this aperture being 60 marked the same as the corresponding rows of punch-pins—that is, "units," "tens," "hundreds," &c. Each bar T is provided with an aperture, R, in the end, for inserting a hook, S, to move these bars.

To punch a check the same is passed in between the plates E and F, which are placed below the follower K of a plunger, L, of a press, M.

The operation is as follows: For example, 65 we will assume that the check is drawn for the sum of seven thousand eight hundred and thirty-six dollars. The check or draft J is cut from the check-book in the manner shown, so that 7 will be the highest numeral of the 70 thousands column. So that the amount of the check cannot be raised, all the other numerals must be punched or perforated but those stating the amount of the check. For this purpose the following punch-pins must be so adjusted that they will not perforate the check, 75 viz: No. 7 on the longitudinal row marked "thousands," No. 8 on the row marked "hundreds," No. 3 on the row marked "tens," and No. 6 on the row marked "units." To accomplish 80 this the sliding bar T of the longitudinal row marked "thousands" is moved until the nu-

meral 7 of this bar appears in the corresponding aperture, Q, when the notch O will be above the pin B on this row and on the transverse row marked "7." The bar T, above the row of pins B, marked "hundreds," is moved until the numeral 8 appears in the corresponding aperture, Q. The other sliding bars T are moved accordingly, &c. If the punch-plate is now depressed, those pins below the notches O will not be depressed, and the corresponding numerals of the check will not be perforated, whereas all the rest are depressed and perforate the check, for the bars T press the punches down. Thus the figures indicating the amount of the check only will remain unpunched, and the amount of the check or draft will be shown in a manner rendering raising or forging of the amount impossible. If the bars T are then moved, the beveled heads C and the beveled sides of the notches O slide on each other, whereby the pins B that have been raised by depressing the plate A, as shown in Fig. 3, will be depressed into the normal position.

This machine is to be used for punching and

perforating not only checks or drafts, but any 25 paper or instrument relating to any distinct sum of money or money value, or numbering.

Having thus fully described my invention, I claim as new and desire to secure by Letters Patent—

30

1. In a machine for perforating checks and drafts, the combination, with the perforated die-plate F, of the punch-plate A, the punch-pins B, and the sliding bars T, with a notch, O, in the under side, substantially as herein shown 35 and described, and for the purpose set forth.

2. In a machine for perforating checks and drafts, the combination, with the perforated die-plate F, of the punch-plate A, the punch-pins B, the slide-bars T, with a notch, O, in 40 the under side, and of the plate P, provided with apertures Q, substantially as herein shown and described, and for the purpose set forth.

SIGMUND ULLMAN.
